UNITED STATES PATENT OFFICE.

GEORGE W. BULLEY, OF AKRON, OHIO, ASSIGNOR TO THE MILLER RUBBER COMPANY, OF AKRON, OHIO, A CORPORATION OF OHIO.

HORN OR AMPLIFIER.

Application filed April 11, 1924. Serial No. 705,891.

To all whom it may concern:

Be it known that I, GEORGE W. BULLEY, a citizen of the United States, and resident of Akron, in the county of Summit and State of Ohio, have invented certain new and useful Improvements in Horns or Amplifiers, of which the following is a specification.

My present invention relates to resonating bodies and particularly to sound amplifying apparatus. My invention is particularly adapted to the manufacture of resonating horns such as are used in the construction of loud speakers and phonographs.

Very little is known about the scientific design of such apparatus either as to the effects of shape, finish or materials, as evidenced by the variety of designs exhibited in such articles now on the market. The general opinion of the public and of manufacturers is that metallic horns, especially when made of thin metals, and some of other hard and sonorant materials tend to vibrate, themselves, in addition to their function of surrounding a vibrating air column and thereby add certain foreign sounds, or impart a "tinny" quality to the speech or music. The objection to such horns is so universal that many efforts have been made to produce horns of non-metallic nature and the majority of such devices now on the market are made of cellular hard rubber, wood, fiber, or glue and plaster compositions. Of these materials, wood can be produced in complicated shapes only at great expense, fiber is difficult to form in the required shapes, so that the article must be made in pieces, the glue and plaster is too breakable and heavy, and cellular hard rubber has surpassed all of these in ease of production, uniformity and tonal quality. Cellular hard rubber horns are molded of one piece construction, and where a complicated shape is required, it is often difficult and sometimes impossible to produce such design in this material. Such a shape is illustrated in the accompanying drawings.

I have found that the flaring or bell portion of a horn is more liable to produce distortion of the sounds than the parts of the horn nearer the diaphragm, and that while cellular hard rubber is an ideal material for that portion of the horn where the ratio of horn thickness to diameter is relatively

small, its advantage over other materials is 55 not so apparent in other parts of the horn. I have found for instance, that the small part of the horn near the diaphragm may be made of aluminum or other metal which may be cast in complicated shapes quite impossible to produce in cellular hard rubber and the remainder of the horn may be made of cellular hard rubber. Such a horn I also find to be better balanced in weight in some shapes of horns. 60 65

In order to insure absolute continuity of the sound passage free from air leaks which would prevent certain sounds from being reproduced and in order to prevent any vibration due to jointed contacts, I mold the rubber and metal portions in interlocking relation. This is done by first casting the metal part having openings therethrough and placing this in a mold for producing the rubber portion. In the molding operation the rubber flows through the openings and interlocks with the metal. No cement, glue, rivets or screws are necessary and an air tight joint is obtained. The metal part may be machined at the small end to accurately 70 75 80 fit the sound box.

In order that my invention may be more readily understood, I have appended hereto a drawing illustrating the same, in which—

Figure 1 is a perspective view of a horn, 85 and

Fig. 2 is a fragmentary sectional view on a larger scale.

Referring by reference characters to this drawing, the numeral 1 designates the metal 90 portion of the horn, and 2 the cellular portion of cellular hard rubber. The metal portion is provided with a plurality of annularly arranged holes 2^a into which the rubber flows in the molding operation, and 95 thus forms a firm interlocking connection. Preferably, the perforated portion is of reduced thickness, formed by rebating the inside of the mouth of the metal portion, so that the inner surface of the rubber portion 100 is flush with the inner surface of the metal portion, and the metal portion may be provided with an external flange 1^a against which the rubber abuts.

It will be understood that the material 105 used in the small part of the horn near the neck, does not have as much effect on the quality of the sound as the material used in

the bell, and while I prefer to use cast metal for the neck of the horn, I do not wish to be limited to metal castings, as the neck might be formed of sheet metal, or other solid material.

Having thus described my invention, what I claim is:—

1. An amplifying horn comprising a metallic neck portion and a hard rubber sound amplifying or bell part, having its inner reduced end molded around the end of the metallic neck, and with its inner surface flush with the inner surface of the metal

neck, means being provided on the neck end for interlocking with the rubber part. 15

2. An amplifying horn comprising a metallic neck portion having an internally rebated end, and a hard rubber sound amplifying part having its inner end molded around said end, and with its inner surface flush with the inner surface of said metal part, means being provided on said metal end for interlocking with the rubber part. 20

In testimony whereof, I affix my signature.

GEORGE W. BULLEY.
